UNITED STATES PATENT OFFICE.

WILLIAM J. SCHWEIGER, OF NEW YORK, N. Y., ASSIGNOR OF ONE-HALF TO
HERMANN APFELBAUM, OF SAME PLACE.

ELECTRIC BELL.

SPECIFICATION forming part of Letters Patent No. 509,050, dated November 21, 1893.

Application filed March 15, 1893. Serial No. 466,168. (No model.)

To all whom it may concern:

Be it known that I, WILLIAM J. SCHWEIGER, a citizen of the United States, and a resident of New York, in the county and State of New York, have invented a new and useful Improvement in Electric Bells, of which the following is a specification.

I will describe an electric bell embodying my improvement, and then point out the novel features in the claims.

In the accompanying drawings Figure 1, illustrates an electric bell containing my improvement, the dome of the bell being omitted. Fig. 2, is a sectional view thereof. Fig. 3, is an exterior view of the same, and Fig. 4, shows a blank from which the armature portion of the bell is formed.

A is a circular base-plate having an annular rim on its upper and lower sides, and is secured to a wall or other support, by screws a .

a' is an opening in the base plate, for the passage of electric wires to the binding posts a^2 a^3 , the post a^2 , being insulated, and the other cast integral with the base-plate.

B B are magnets secured to a lug, a^4 , extending from the base-plate, and cast integral therewith.

C is an armature secured to a resilient spring, c , attached to a lug, a^5 , of the base-plate. This armature is provided with an arm, c^2 , having a hammer, c' arranged to act on the exterior of the dome D. The arm c^2 , is bent sufficiently at c^3 , to pass beneath the rim of the dome and vibrate within a notch, a^6 , formed in the upper rim a^7 , of the base-plate. If desired, the armature with its arm and hammer may be stamped out from a plate of sheet metal, as shown in Fig. 4, and the arm afterward bent at right-angles to the armature approximately.

E is a make and break contact device, comprising the spring c , resting against an adjustable and insulated screw e' , in a post, a^8 , and in electrical connection with the magnets B B, and binding post a^2 , by means of the wire e^2 . The spring c , is in electrical connection with the binding post a^8 , by means of the wire e^3 . Single stroke mechanism, in lieu of vibrating mechanism may be employed if de-

sired. The dome D, has its rim arranged in close proximity with the rim a^7 , of the base-plate, and the magnets, armature and contact breaking mechanism, are wholly inclosed within the dome of the said bell. This dome is detachably secured to a post, a^8 , integral with the base-plate. By this construction I provide a bell, neat in appearance, and compact in arrangement of parts. The hammer is arranged to operate on the exterior of the bell, and the working parts are wholly inclosed within the dome of the bell, whereby a louder tone is obtained, and dust and other substances tending to impair the efficiency of the bell, are prevented from obtaining access to the interior parts thereof.

I claim—

1. In an electric bell, the combination, of a base plate provided with an annular rim, a dome having its rim arranged in close proximity to that of the base plate, an armature having an arm provided with a hammer arranged to act on the exterior of the dome, the said arm being adapted to vibrate within a notch contained in the rim of the base-plate, substantially as described.

2. In an electric bell, the combination of a circular base plate having a rim on its upper and lower sides, magnets secured to a lug integral with the base plate, an armature therefor, provided with a hammer arranged to act on the exterior of the bell, and connected to the armature by an arm adapted to vibrate within a notch in the adjacent rim of the base plate, and a dome detachably secured to a post integral with the base plate, and having its rim arranged in close proximity with the adjacent rim of the base plate, and wholly inclosing the mechanism operating the hammer, substantially as described.

3. In an electric bell, as described, the circular base plate A, having an opening, a' , for the passage of electric wires to binding posts within the dome of the bell, the said plate having the annular rims on its upper and lower sides, the post a^8 , lugs a^4 , a^5 , a^9 , and binding post a^8 , cast integral therewith, substantially as described.

4. In an electric bell as described, an arma-

ture C, hammer c' , and arm c^2 containing the loop c^3 , comprised in one integral piece of sheet metal, the arm c^2 being bent at right angles approximately to the armature C, and the flat sides of the latter being in the same plane as the flat sides of the hammer, as specified.

In testimony that I claim the foregoing as

I my invention I have signed my name, in presence of two witnesses, this 10th day of March, 1893.

WILLIAM J. SCHWEIGER.
